UNITED STATES PATENT OFFICE

164,656

WINDSHIELD DEFROSTER

Harold Charles Taylor, Birmingham, England, assignor to Joseph Lucas Limited, Birmingham, England, a company of Great Britain

Application February 20, 1948, Serial No. 144,649
In Great Britain June 18, 1947

Term of patent 7 years

(Cl. D14—6)

To all whom it may concern:

Be it known that I, Harold Charles Taylor, a subject of the King of Great Britain and Northern Ireland, residing at 90 Crophorne Road, Shirley, Birmingham, England, have invented a new, original, and ornamental Design for a Windshield Defroster, of which the following is a specification, reference being had to the accompanying drawing, forming part thereof.

Figure 1 is a front perspective view, Figure 2 a rear perspective view, Figure 3 a plan, Figure 4 an end view and Figure 5 a sectional end view on the line 5—5 (Figure 2) of a windshield defroster embodying my design.

I claim:

The ornamental design for a windshield defroster, as shown.

HAROLD CHARLES TAYLOR.
